UNITED STATES PATENT OFFICE.

HAZEL V. GRAYSON, OF ATHENS, OHIO.

DESIGN FOR A GAS HEATER.

Application filed April 28, 1925. Serial No. 13,245. Term of patent 14 years.

To all whom it may concern:

Be it known that I, HAZEL V. GRAYSON, a citizen of the United States, residing at Athens, in the county of Athens and State of Ohio, have invented a new, original, and ornamental Design for Gas Heaters, of which the following is a specification, reference being had to the accompanying draw-

ing, forming part of this application, and wherein the figure is a front view of the heater.

I claim:

The ornamental design for a gas heater, as shown.

Dated April 24, 1925.

HAZEL V. GRAYSON.
